UNITED STATES PATENT OFFICE.

JAMES N. MOODY, OF SOUTH BOSTON, VIRGINIA.

ATTACHMENT FOR BEDS.

No. 930,554.

Specification of Letters Patent.

Patented Aug. 10, 1909.

Application filed November 25, 1908. Serial No. 464,503.

To all whom it may concern:

Be it known that I, JAMES N. MOODY, citizen of the United States, residing at South Boston, in the county of Halifax and State 5 of Virginia, have invented certain new and useful Improvements in Attachments for Beds, of which the following is a specification.

This invention is a device to hold a curtain 10 over a bed, to hang between the pillows and the sleepers, so that the persons may lie facing each other and not get each other's breath.

The object of the invention is to prevent 15 the transmission of contagious diseases and to promote health by the prevention of infection.

The invention is illustrated in the accompanying drawings in which—

20 Figure 1 is a side elevation of the device as applied to a bed; Fig. 2 is a detail in perspective showing the block for holding the curtain rod; Fig. 3 is a front view.

Referring specifically to the drawings, 6 25 indicates a hook adapted to engage over the top rail of the head of a metal bed or over the upper edge of the head of a wooden bed, and this may be provided with a thumb screw 7 for holding it in place. Depending 30 from this hook is a support which may consist of a single rod, or of an extensible rod consisting of a tubular part 8 and a rod 9 slidable in the tube, and held in place by a thumb screw 10. This extensible device will 35 allow the invention to be adjusted to fit any bed. At the lower end the rod 9 is provided with a block 11 having a hole 12 therein and notches 13 in the top of the block adjacent the hole. One of the notches is located in 40 front of the hole and the others on opposite

sides thereof. A curtain rod 14 is provided with a depending pivot or finger 15 at the inner end, which fits in the hole 12 and which may be turned therein. A curtain 16 is suspended from the rod.

When the rod is turned to lie in the front 45 notch, the curtain will hang down between the pillows of the bed and form a shield to prevent the breath of one person passing to the other. By swinging the rod until it engages in one of the side notches the curtain 50 will hang against the head of the bed out of the way, and the bed may be used as usual, and if necessary for this latter purpose the rod 9 may be pushed up to raise the curtain 55 above the pillows.

This simple device will be found very useful in connection with such diseases as tuberculosis where the isolation of a sufferer is desirable.

The device may be modified in various 60 ways within the scope of the invention, not being limited to the exact embodiment shown and described.

I claim:

An attachment for a bed, comprising a rod 65 having means at its upper end to attach the same to the head of a bedstead, a block attached to the lower end of the rod and provided with a bearing and notches in front of and at the side of said bearing, a swinging 70 rod having a pivot at its inner end mounted in said bearing, and a curtain suspended from said swinging rod.

In testimony whereof, I affix my signature 75 in presence of two witnesses.

JAMES N. MOODY.
